R. H. Leedy,

Shark Arrester.

No. 92,617.

Patented July 13, 1869.

A. C. Johnston
Wesley Johnston

R. H. Leedy, by his attorney, A. C. Johnston

United States Patent Office.

ROBERT H. LECKY, OF ALLEGHENY CITY, PENNSYLVANIA.

Letters Patent No. 92,617, dated July 13, 1869; antedated June 29, 1869.

IMPROVEMENT IN EXHAUST-DEVICE FOR LOCOMOTIVE SMOKE-STACKS.

The Schedule referred to in these Letters Patent and making part of the same.

To all whom it may concern:

Be it known that I, ROBERT H. LECKY, of the city and county of Allegheny, in the State of Pennsylvania, have invented a new and useful Improvement in "Steam-Exhaust for Locomotive-Chimneys and Flues;" and I do hereby declare the following to be a full, clear, and exact description thereof, reference being had to the accompanying drawings, and to the letters of reference marked thereon.

The nature of my invention consists in providing the exhaust-blast pipe of a locomotive with a stationary centre-piece, and with a movable sleeve on the blast-pipe; said centre-piece and sleeve being so constructed and arranged with relation to each other that the force of the blast may be regulated to any degree desired.

To enable others skilled in the art to make and use my invention, I will proceed to describe its construction and operation.

In the accompanying drawings, which form part of my specification—

Figure 1 is a front elevation of my improvement in blast-pipe, or steam-exhaust, for locomotive-chimneys.

Figure 2 is a vertical section of the same.

In the drawings—

A is a bell-mouth sleeve, which is arranged on the upper branch of an ordinary blast-pipe, C, of a locomotive-chimney or stack, (which is represented by dotted lines in fig. 2.)

This sleeve A is provided with two or more slots, D, in which is placed a pin, i, secured in the pipe C.

To one side of the sleeve A is attached arm f, to which is attached a lever leading to the engineer, and so arranged that said lever will move the arm f back and forward, for the purpose of turning the sleeve A, which turning will raise or lower the sleeve, through the medium of the slots D and pins i.

By raising and lowering the sleeve A, the annular opening around the centre-piece B may be increased or diminished at will, and thereby increase or diminish the force of the blast.

The centre-piece B (the form of which is clearly indicated in fig. 2) is held in the desired position by means of rods e, which should be attached to the pipe C, and so arranged as to hold the centre-piece B central to the opening of the upper branch of the pipe C.

An opening is made in the centre of the centre-piece B, so that by and through the centre openings of piece B, and the annular opening around it, a side and centre-currents are created in the stack.

The ends O of the pipe C are attached to the exhaust-pipes of the engines in the usual manner.

What I claim as new, and desire to secure by Letters Patent, is—

The combination of the sleeve A with the inverted cone B, said sleeve and cone being constructed and arranged with relation to each other substantially as herein described.

R. H. LECKY.
